WILLIAM E. SMITH, OF MILLTOWN, NEW JERSEY, ASSIGNOR TO THE INTERWOVEN MILLS, INC., OF NEW BRUNSWICK, NEW JERSEY, A CORPORATION OF NEW JERSEY.

CIRCULAR-KNITTING MACHINE.

1,347,186.

Specification of Letters Patent. Patented July 20, 1920.

Application filed May 17, 1919. Serial No. 297,763.

To all whom it may concern:

Be it known that I, WILLIAM E. SMITH, a citizen of the United States, residing at Milltown, in the county of Middlesex and 5 State of New Jersey, have invented certain new and useful Improvements in Circular-Knitting Machines; and I do hereby declare the following to be a full, clear, and exact description of the invention, such as 10 will enable others skilled in the art to which it appertains to make and use the same.

My invention consists in the novel features hereinafter described reference being had to the accompanying drawings which illustrate 15 an embodiment of my invention selected by me for purposes of illustration, and the said invention is fully disclosed in the following description and claims.

The object of my invention is to provide 20 simple mechanism for knitting seamless tubular fabric by circular knitting in which a segmental portion of the tubular fabric may be made shorter than another segmental portion of the fabric by omitting partial 25 courses of stitches through the shorter segment of the fabric, and thereby forming partial courses of stitches in the segment to be lengthened between adjacent circular courses of stitches. More specifically, my 30 invention relates to a stocking knitter and contemplates the provision of means whereby the top portion of the foot of a stocking is made shorter than the corresponding sole portion of the foot, by omitting partial 35 courses of the circular knitting through the top of the foot, and thereby knitting partial courses in the sole portion of the foot between adjacent circular courses so that the top portion of the foot shall be from a half 40 size to a size shorter than the corresponding sole portion of the foot, to fashion the stocking to the shape of the foot, and prevent the formation of wrinkles upon the top of the foot and instep when the stocking is worn. 45 To this end my invention consists in providing mechanism whereby during the knitting of circular work, as in the formation of the foot of the stocking, those needles which knit the segmental portion of the 50 tubular fabric forming the top of the foot are, at predetermined times, prevented from forming stitches with the main knitting thread, which is supplied to all the needles, and preferably by placing such needles in 55 an inoperative position with respect to the

knitting cam or cams therefor and feeding the thread thereto below the latches thereof, so that when the needles are again operated normally for the drawing of a stitch, they will cast off the thread delivered to them below their latches, thus throwing it to the center of the tube where it forms a float and is subsequently cut out, thus eliminating or omitting a certain number of partial courses from that segment of the tubular fabric which forms the top of the foot of a stocking.

In the accompanying drawings I have shown my invention embodied in a stocking knitter of the type known as the Banner machine (see patent to Hemphill, 933,443, September 7, 1909), and in the said drawings I have illustrated so much of the Banner machine, in connection with the additional parts applied thereto for the purpose of carrying out my present invention, as are necessary for a complete understanding of my invention. I have also illustrated diagrammatically the stocking produced by my improved mechanism.

In the said drawings,

Fig. 1 represents a top plan view of a stocking knitter of the well known type of "Banner" machine, having embodied therein, my present invention.

Fig. 2 is a partial end elevation of the machine.

Fig. 3 is a perspective view illustrating the mechanism which I have embodied in the Banner machine for the purpose of carrying out my invention, certain portions of the machine being omitted for the sake of clearness, as for example, the bracket carrying the thread guides and knitting cams, and the pickers.

Fig. 4 is an enlarged top plan view of a portion of my improved apparatus including the auxiliary needle elevating cam, the means for supporting and actuating the same, and means for holding the adjacent picker out of the path of the needle nibs during the production of a partial course, the needle elevating cam being illustrated in retracted position.

Fig. 5 represents a similar view of the same apparatus showing the needle elevating cam in operative position and the picker held out of the path of the needle nibs.

Fig. 6 is a top plan view of the auxiliary lowering cam and the mechanism for sup-

porting and actuating the same, the cam being shown in operative position with respect to the needle cylinder.

Fig. 7 is an enlarged detail view showing 5 the cam and lever for throwing the mechanism for knitting a partial course through the sole of the foot or elsewhere in the stocking into and out of operation, and the parts immediately connected therewith.

10 Fig. 8 is a side view of the cam wheel and cam shown in Fig. 7.

Fig. 9 is a detail view showing one of the 15 pattern wheels of the Banner machine, the pattern chain engaging the same, and cam carried by one of the chain links for locking the partial course mechanism out of operative position.

Fig. 10 is a plan view of the cam ring of 20 the machine as it would appear if cut and spread out in a plane and showing the auxiliary cam for raising and lowering certain of the needles of the circular series into and out of operative position with respect to the knitting cams.

25 Fig. 11 is a diagrammatic view representing the different relative positions of the long and short nib needles during circular work when a partial course is to be omitted from a segment of the tubular fabric and 30 the position of the main knitting thread as it is fed to said needles.

Fig. 12 is a diagrammatic view of a stocking produced by the mechanism illustrated in the preceding figures.

35 Fig. 13 represents diagrammatically the circular series of needles and illustrates the manner in which the main knitting thread is fed to and knit thereby during the production of circular and partial courses, during 40 circular work.

45 In carrying out my invention I provide the ordinary and well known Banner stocking knitter with a circular series of needles of ordinary form, the needles knitting the rear portion of the leg of the stocking, the heel, sole and toe, one of which is illustrated at 100 in Fig. 11, being provided with a short nib indicated at 101, the needles knitting 50 the front of the leg of the stocking and top of the foot, one of which is indicated at 102 in Fig. 11, being provided with a long nib indicated at 103. The Banner machine is provided with the usual knitting cams, indicated at 104, the structure and operation 55 of which need not be specifically described herein, as they are constructed and operate in the usual and well known way (see Fig. 10), and the machine is also provided with the usual raising and lowering cams, indicated at 60 105-106 which are mounted on a vertically movable slide 107 and are adapted to be actuated under the control of the pattern mechanism through a link 108 and bell crank lever 109, for example, as shown in Fig. 10, whereby they may be raised and

lowered at the beginning of and at the conclusion respectively of reciprocating work. These cams 105-106 are so constructed as to engage only the long nib needles and when the slide 107 is raised at the beginning of 70 reciprocating work, the long nib needles, which knit the front part of the leg and top of the stocking, will be elevated by the cam 106 to such a position that they will not be actuated by the knitting cam, the needles 75 being maintained in elevated position by friction between the needles and their grooves, and also by frictional contact with a surrounding coil spring, indicated at 110 in Fig. 2, in the usual and well known manner. When the reciprocating work is completed, the cams 105 and 106 are lowered and the lowering cam 105 causes the long nib needles to be restored to operative relation with the knitting cam during the first 80 circular movement of the knitting cylinder. This is the ordinary operation of the Banner machine and forms no part of my present invention.

85 In embodying my invention in the well known Banner machine an auxiliary raising cam, indicated at 1, and auxiliary lowering cam, indicated at 1^a, on opposite sides of the knitting cam, are so arranged that when in operative position they will engage the 95 long nibs 103 of the needles 102, but do not engage the short nibs 101 of the needles 100. When the machine is knitting circular work, as in the foot of the stocking, if the auxiliary cams 1 and 1^a are in operative position, 100 the long nib needles will be raised by the raising cam 1 so that as they pass the thread guide or guides, indicated at 111 in Fig. 1, which are stationarily supported and located adjacent to the knitting cam, the main knitting thread, whether comprising a single 105 yarn or a plurality of yarns, will be fed to the long nib needles 102 below the latches thereof, as shown in Fig. 11, and as soon as each needle has received its thread in this position, and has passed the stitch forming or knitting cams 104 of the machine, it will be drawn down by the auxiliary cam 1^a, thereby preventing the thread from getting into the hook of the needle. When the next 110 circular course is knit, the needles 102 are not raised by the auxiliary cam 1 and receive the thread in the hooks thereof, and are actuated by the knitting cam 104 to form a stitch with the thread which has been fed 115 to the hooks of the needle, while the thread previously fed below the latch is cast off to the center of the cylinder and becomes a float thread extending from one side of the tube across to the other, as shown at 112 in 120 Fig. 13, which is afterward cut out at points indicated by the dotted lines x-x in Fig. 13, after the completion of the stocking or other tubular fabric. By operating these auxiliary raising and lowering cams par- 125

5 tial courses can be formed at any point during circular knitting, and corresponding partial courses omitted from the other segment of the fabric, thus making the segment containing the partial courses longer than the segment from which the partial courses are omitted, as will be readily understood. In the machine shown in the drawings, I have illustrated mechanism under control of the pattern mechanism of the Banner machine whereby these partial courses can be formed when desired at intervals through a section of circular work, as the foot of the stocking, for the purpose 10 of making the sole of the stocking longer than the corresponding segment of circular knitting forming the top of the foot, and the mechanism herein shown and described, is constructed to produce a partial course in 15 the sole portion, and suppress a corresponding partial course in the top of the foot in every fourth course during the knitting of the foot portion of the stocking. My invention is not confined to knitting the partial 20 course in every fourth course, as it may be in every other course, or at other desired intervals throughout the foot or portions of the foot only, as hereinafter more fully explained.

25 80 85 90 95 100 105 110 115 120 125 130

30 The auxiliary raising cam 1 consists of a curved plate having an inclined upper edge, and is conveniently mounted on a horizontal slide 2 supported in an actuating groove in a block 114 secured to the top plate 115 of 35 the Banner machine. The slide 2 is actuated in this instance by means of a lever 28 pivoted on the block 114, and provided at one end with a yoke or slotted portion engaging a pin 117 on the slide, the other end of the 40 lever being connected to an actuating rod 27, which receives its motion from a horizontal lever 23 pivotally secured to and beneath the top plate 115 of the machine, and actuated by a segmental cam 11 on a cam 45 wheel 10 which is so driven as to make one complete revolution to each four circular courses, or in other words four revolutions of the needle cylinder 116. The cam wheel 10 is shown in detail in Fig. 8, and is provided on its outer face with a segmental cam 11 which extends in this instance three quarters of the way around the cam wheel leaving an open space indicated at 11^a, which corresponds to the one course in four during 50 which a partial course is suppressed in that segment of the fabric knit by the long nib needles. If it is desired to suppress the partial course in every other course of knitting, it would simply be necessary to cut out 55 the opposite quarter segment of the cam 11, indicated at 11^b between the dotted lines 11—11^c, and by so timing this cam wheel, and arranging the cam thereon, any desired interval between the suppressed courses can 60 be secured. The lever 23 is provided at its 65 rear end with an inwardly extending arm 23^b to engage the cam 11 on the cam wheel 10 and the lever is held in engagement with the cam wheel, and drawn toward the cam wheel by means of a spring indicated at 23^a, 70 in this instance secured to the frame of the machine. The forward end of the lever 23 is bent upwardly to form a vertically disposed arm 24 provided in its upper end with an aperture through which the rod 27, previously referred to, loosely extends, and is provided with a cotter pin 27^a (or collar). On the rod 27 is a loose sleeve 25, the outer end of which engages the arm 24 of the lever 23, while the inner end of the sleeve engages 75 a coil spring 26, the other end of which engages a cotter pin 27^b (or collar) on the rod 27. It follows from this construction that when the lever 23 is moved in one direction by the cam 11, as indicated by the arrow in Fig. 7, the arm 24 of the lever will bear against the sleeve 25 and spring 26 and move the rod 27 yieldingly (to the left in Figs. 3 and 7) in a direction to effect the retraction of the slide 2 and auxiliary raising cam 1, 80 and the parts will be held in this position as long as the lever 23 is engaged by the cam 11, that is to say, in the present construction, during three circular courses, during which the auxiliary raising cam is held out of operative position and all the needles of the circular series knit to form circular courses. When the arm 23^b of the lever 23 passes off of the cam 11 the lever will be actuated by the spring 23^a to move the lever in a direction opposite to that indicated by the arrows in Fig. 7, thereby causing the arm 24 to draw the rod 27 in such direction (to the right in Figs. 3 and 7), as to move the slide 2 and auxiliary cam toward the knitting cylinder 116 and into operative relation with the long nib needles, whereby all of the long nib needles will be raised by the inclined face of the auxiliary raising cam 1, as indicated in Fig. 3, said needles being 85 raised to the position indicated in Fig. 11 so as to receive the thread below the latches thereof. Before the next course is reached in the machine, the lever 23 will be again actuated by the cam 11 to withdraw the auxiliary raising cam 1. 90 95 100 105 110 115 120 125 130

45 50 55 60 65 70 75 80 85 90 95 100 105 110 115 120 125 130

116 117 117^a 117^b 117^c 118 119 120 125 130

The auxiliary lowering cam 1^a is located on the opposite side of the stitch forming cams from the auxiliary raising cam 1, as before stated, and is preferably carried by a slide 2^a mounted on the block 114^a. This cam is moved into and out of operative position, in this instance by means of a bell crank lever 32, one arm of which is forked or slotted to engage a pin 117^a on the slide, while the other arm is connected to a rod 31, the outer end of which extends loosely through an aperture in a horizontal lever 30 and is provided with a coil spring 118 on the outer side of the lever 30, the outer end 130

of which engages a cotter pin 119 extending through the rod 31 (or collar secured thereto), the said rod 31 being provided with a cotter pin 120 (or collar), which is engaged 5 by the inner face of the lever 30. The lever 30 is pivoted to the top plate 115 of the machine, and has its forwardly extending end located in such position that it will be engaged by the end of the sleeve 25 on the rod 10 27 when the said sleeve is pushed in far enough by the arm 24 of the lever 23, and the lever 30 is actuated in the opposite direction by the spring 30^a which actuates the said lever and the rod in the direction of 15 the arrow in Fig. 3, and tends to hold the cam 1^a normally in opposite position.

During the knitting of a circular fabric in which partial courses are to be suppressed, as in the foot of the stocking, it is not necessary to withdraw the auxiliary lowering cam every time the auxiliary raising cam is withdrawn as the presence of the auxiliary lowering cam in operative position has no effect unless the long nib needles have been raised. 20 While obviously the auxiliary lowering cam 1^a could be withdrawn simultaneously with the auxiliary raising cam if desired, I prefer to allow it to remain in operative position during the knitting of the tubular portion 25 of the fabric in which partial courses at the desired intervals are omitted or suppressed, and to simply insure the withdrawal of the auxiliary lowering cam during the knitting of other portions of the fabric as the leg and heel and toe of the stocking. Consequently 30 the lever 30 will be so located at its forward end that it will not be engaged by the sleeve 25 during the normal movements of the sleeve to move the auxiliary raising cam out of operative position, but will be actuated by an additional movement of the lever 23 beyond that imparted to it by the actuating cam 11, at which time both auxiliary cams will be locked out of operative position, so 35 that the toe pocket of the stocking can be knit by reciprocating work, and the leg of the next stocking may be knit by circular work, and the heel pocket of the next stocking knit by reciprocating work, before the auxiliary cams are again allowed to operate. 40 To effect this I employ a finger 22 on a rock shaft 21 mounted in a bracket secured to the side of the machine frame (see particularly Fig. 3), said rock shaft being provided with 45 an arm 20 connected by a vertical rod 19 which depends therefrom and passes through a guiding bracket 18^a, secured to the frame of the machine, the lower end of the rod 19 extending through the guide 18^a and in a 50 position to be engaged by cam 51 on the periphery of a cam wheel 50 forming part of the pattern mechanism of the Banner machine. The vertical rod 19 is also provided with a forwardly extending locking arm 18 55 rigidly and preferably adjustably secured

thereto in position to be engaged and raised by a cam 15 on a horizontal rock shaft 121 mounted in a bracket on the front portion of the machine frame, said rock shaft being provided with an arm 16 normally acted upon by a spring 16^a to depress said arm into engagement with the pattern chain 17 of the Banner machine and hold the cam 15 out of operative engagement with the arm 18. The pattern chain 17 is provided in this instance with a stop link, as shown in Fig. 9, which carries a cam 122 in position to engage the arm 16 and raise it, thereby depressing the cam 15 into engagement with the arm 18 and raising the rod 19, which through its connection with the arm 20 rocks the shaft 21 and moves the finger 22 in a direction toward the lever 23. This action takes place on the conclusion of the formation of the main body of the foot of the stocking and preferably a predetermined number of courses before the commencement of the knitting of the toe pocket, which is secured by proper placing of the link carrying the cam 122 in the pattern chain 17, and it also occurs while the lever 23 is in engagement with the cam 11, so that the forward end of the lever 23 is held in its inwardly pressed position with the auxiliary raising cam out of operative position, and is not permitted to move outwardly under the influence of the spring 23^a. After a plurality of courses of circular knitting have been knit, which preferably form what I term the toe band of the stocking, being the courses immediately adjacent to the toe pocket, and in which I prefer not to have any partial courses formed, the pattern wheel 50 is caused to move to bring the cam 51 into engagement with the lower end of the rod 19 and give it a further movement upward, which movement is transmitted through the arm 20 and rock shaft 21 to the finger 22, and pushes inwardly on the lever 23, thus causing its arm 24 to impart a further inward movement to the sleeve 25. This extra movement of the sleeve 25 does not affect the auxiliary raising cam 1, which is already out of operative position, and the additional movement is taken up by the spring 26. The additional movement of the sleeve 25 will cause it to engage the lever 30 and actuate it to withdraw the auxiliary lowering cam 1^a into operative position, and at the same time prevent any further return of either the auxiliary cams 1, 1^a, to operative position so long as the rod 19 remains in engagement with the cam 51 on the pattern wheel 50. As soon as the cam 51 has taken charge of the rod 19, the further movement of the pattern chain 17 removes the cam 122 from engagement with the arm 16, allowing said arm to drop under the influence of its spring 16^a, and withdrawing the cam 15 from engagement with the arm 18, which has now been raised to a higher position, and the 130

parts remain in this position during a revolution of the pattern wheel 50, during which time the toe pocket is knit by reciprocating work in the usual manner, the leg of the next 5 stocking is knit by circular work and the heel pocket formed by reciprocating work, when the rod 19 will pass off of the cam 51, thus causing the finger 22 to release the lever 23 and permit the cam 11 on the cam 10 wheel 10 to resume control of the auxiliary raising cam, and also causing the sleeve 25 to release the lever 30 and permit the spring 30^a acting on said lever 30 to return the auxiliary lowering cam to its operative position. 15 In the Banner machine there are provided the usual pickers for throwing certain of the short nib needles into and out of operative position during narrowing and widening, in knitting a heel and toe pocket of 20 the stocking. These pickers are located on opposite sides of the stitch forming cams and each comprise a short arm 123 pivotally mounted on a stud 124 having an axis inclined to the vertical and provided with a 25 light spring 125 normally holding the outer end 126 of the picker in light engagement with and resting upon the nibs of the needles as they are carried around past the knitting or stitch forming cams. This is the usual 30 construction in the Banner machine and the operation of the pickers will not be more particularly described, as it has no bearing on my present invention. Referring, however, to the picker located adjacent to the 35 auxiliary raising cam 1, it follows that if this auxiliary raising cam is moved into operative position and raises the long nib needles, in the manner previously described, the adjacent picker would pass off of the 40 last preceding nib and there would be nothing to support its outer end, which would then fall under the influence of its light spring into such position as to be likely to be struck by the needle nibs when they were 45 restored to their normal position. In order to prevent this, I provide means so that whenever the auxiliary raising cam is moved toward the cylinder into operative position with respect to the long nib needles, the adjacent 50 picker is held against the tendency of its spring to depress it, or slightly raised and held so long as the auxiliary cam 1 is in operative position, so as to prevent the picker from falling below its normal position and being struck by the nibs of the 55 needles, which would tend to break them. To this end I provide on the slide 2 carrying the auxiliary raising cam 1, a hook 3 which is so formed that when the slide 2 is 60 moved inwardly, this hook will engage the picker adjacent to its point of pivoting, as indicated in Fig. 5, and slightly raise the inner end of the picker and hold it in this position until the slide 2 is again retracted, 65 thus preventing the picker from dropping

when the long nibs of the needles are raised above the picker by the auxiliary cam 1.

In Fig. 12 I have illustrated diagrammatically a stocking made by the particular machine illustrated in the drawings, in which 70 diagram A represents the usual ribbed top, B the leg of the stocking, which is usually knit with circular courses of plain knitting, C the top of the foot of the stocking, C' the sole portion of the foot, D the heel 75 pocket, E the toe pocket, and F what is termed the high spliced portion of the leg immediately above the heel, in which a splicing thread is usually thrown in through the rear portion of the leg for the purpose 80 of thickening the stocking above the heel. In the foot of the stocking I have represented by lines c, the three complete circular courses and by the lines c' the partial courses occurring as every fourth course in the sole 85 portion only, the corresponding partial course being suppressed or omitted in the part extending over the top of the foot, it being understood that these partial courses may be formed at the stated intervals (or at 90 any other desired intervals) throughout the entire foot, or they may occur in special parts of the foot, by slightly modifying the pattern control mechanism. As stated here-tofore, I prefer to knit a plurality of courses 95 of circular work only, adjacent to the toe pocket to form what I term a toe band, which is indicated at c² for the purpose of insuring a proper joining of the upper edge 100 of the toe pocket with the end of the top of the foot at the point indicated at e, in the usual manner of forming seamless hosiery, by looping or otherwise. It will be seen that as the sole portion, indicated at C', of the foot contains a considerable number of 105 partial courses not contained in the upper portion C of the foot, it will be considerably longer than the corresponding segment C of the foot of the fabric. As a matter of fact, I prefer that the sole segment C' of the 110 foot should be approximately from three quarters to an inch longer than the corresponding segment C of the top of the foot, and this fashions the stocking to fit the human foot, providing ample room for the 115 sole, heel, and toe, and causing the upper part of the foot and instep of the stocking to lie smoothly and avoid wrinkles therein. This also prevents the dragging down of the high spliced portion of the stocking above 120 the heel, which occurs frequently where the upper and lower segment of the foot portion are of the same length, and otherwise contributes to a more perfect fit and adaptation of this seamless hose to the configuration of 125 the human foot.

It will be understood that by slightly modifying the pattern mechanism partial courses can be formed in any part of the circularly knit tubular fabric, as in the leg of 130

the stocking, if desired, for example, immediately above the heel, and it is also obvious that in knitting any form of tubular fabric by circular knitting on this machine, a segmental portion can be provided with partial courses and the corresponding partial courses suppressed or otherwise omitted in the other segment of the fabric, so as to make the segment of a tubular fabric containing such partial courses longer than the other.

The process of knitting for the production of such a fabric, for seamless hosiery or other purposes, and the fabric itself, are not herein claimed as the same form the subject matter of another application filed by me May 5, 1919, Serial No. 294,784.

What I claim and desire to secure by Letters Patent is:—

20 1. In a circular knitting machine, the combination with a circular series of needles, stitch forming cam mechanism for actuating all of said needles, to form a circular course of stitches, and a thread guide for feeding a knitting thread circularly to all of said needles during circular work, certain consecutive needles for knitting a segmental portion of the tubular fabric being provided with longer nibs than those of the other needles of the series, of an auxiliary raising cam for engaging the long nib needles only, for raising them out of operative relation with the stitch forming cam mechanism during circular work, an auxiliary lowering cam for engaging said long nibs and lowering them into operative relation with the stitch forming cam mechanism, said auxiliary raising cam being movable in directions toward and from the circular series of needles, into and out of operative relation with the long nib needles, and means for moving said auxiliary raising cam into and out of operative position with respect to the long nib needles, whereby partial courses of 35 stitches may be knit between adjacent circular courses of the tubular fabric with the same knitting thread.

2. In a circular knitting machine, the combination with a circular series of needles, stitch forming cam mechanism for actuating all of said needles during circular work, and a thread guide for feeding a knitting thread circularly to all of said needles during circular work, certain consecutive needles for knitting a segmental portion of the tubular fabric being provided with longer nibs than those of the other needles of the circular series, of auxiliary raising and lowering cams located on opposite sides of the stitch forming cam mechanism for engaging the long nibs only of the needles, said auxiliary raising cam being movable toward and from the circular series of needles, into and out of operative relation with respect to said long nibs, and mechanism for actuating said aux-

iliary raising cam to move it into and out of operative relation with said long nibs, whereby partial courses of stitches can be knit between adjacent circular courses of stitches with the same thread.

3. In a stocking knitter, the combination with a circular series of needles, stitch forming cam mechanism for operating said needles during circular and reciprocating work, means for feeding thread to said needles during circular and reciprocating work, elevating and depressing mechanism for moving a group of successive needles which knit the front of the leg and top of the foot of the stocking into and out of operative relation with the stitch forming cam mechanism, and means for actuating said elevating and depressing mechanism at the beginning and conclusion of reciprocating work, of auxiliary raising and lowering cams for engaging said group of successive needles independent of said elevating and depressing mechanism, and movable toward and from the circular series of needles, into and out of operative position, and means for moving said auxiliary cams into and out of position with respect to said group of successive needles, during circular work, to omit the formation of a partial course of stitches in the segmental portion of the fabric formed by said group of successive needles.

4. In a stocking knitter, the combination with a circular series of needles, a group of needles for knitting the front of the leg and top of the foot being provided with long nibs, and the remaining needles being provided with short nibs, stitch forming cam mechanism for engaging the nibs of all the needles, means for supplying thread to the needles for circular and reciprocating work, vertically movable elevating and depressing cams for engaging the long nib needles, and means for shifting said cams at the beginning and conclusion of reciprocating work, of auxiliary raising and lowering cams located on opposite sides of the stitch forming cam mechanism, for engaging the long nib needles, and controlling means operable during circular work for moving said auxiliary raising cam into and out of operative position at intervals to effect the formation of a partial course of stitches.

5. In a stocking knitter, the combination with a circular series of needles, a group of needles for knitting the front of the leg and top of the foot being provided with long nibs, and the remaining needles being provided with short nibs, stitch forming cam mechanism for engaging the nibs of all the needles, means for supplying thread to the needles for circular and reciprocating work, vertically movable elevating and depressing cams for engaging the long nib needles, and means for shifting said cams at the beginning and conclusion of reciprocating work,

of auxiliary raising and lowering cams located on opposite sides of the stitch forming cam mechanism, for engaging the long nib needles, and controlling means operable during circular work for moving said auxiliary raising cam into and out of operative position at intervals to effect the formation of a partial course of stitches, and means for moving said auxiliary raising and lowering cams out of operative position, and holding them out of operative position during reciprocating work.

6. In a stocking knitter, the combination with a circular series of needles, a group of needles for knitting the front of the leg and top of the foot, being provided with long nibs, and the remaining needles being provided with short nibs, stitch forming cam mechanism for engaging the nibs of all the needles, means for supplying thread to the needles for circular and reciprocating work, vertically movable elevating and depressing cams for engaging the long nib needles, and means for shifting said cams at the beginning and conclusion of reciprocating work, of auxiliary raising and lowering cams located on opposite sides of the stitch forming cam mechanism, for engaging the long nib needles, and controlling means operable during circular work for moving said auxiliary raising cam into and out of operative position at intervals to effect the formation of a partial course of stitches, and means controlled by the pattern mechanism of the machine for holding both of said auxiliary cams out of operative position during the knitting of the heel and toe and leg of the stocking.

7. In a stocking knitter, the combination with a circular series of needles, a group of needles for knitting the front of the leg and top of the foot, being provided with long nibs, and the remaining needles being provided with short nibs, stitch forming cam mechanism for engaging the nibs of all the needles, means for supplying thread to the needles for circular and reciprocating work, vertically movable elevating and depressing cams for engaging the long nibs, and means for shifting said cams at the beginning and conclusion of reciprocating work, of an auxiliary raising cam and an auxiliary lowering cam located on opposite sides of the stitch forming cam and movable into and out of operative relation with the long nib needles, an actuating lever for moving said cams into and out of operative relation, a controlling cam for operating said lever to move the auxiliary raising cam into and out of operative position during certain predetermined courses of knitting, and means controlled by the pattern mechanism for imparting additional movement to said lever, for moving the auxiliary lowering cam out of operative position, and holding both of said auxiliary cams out of operative position.

for supporting said picker when the auxiliary raising cam is in operative position.

8. In a stocking knitter, the combination with a circular series of needles, a group of needles for knitting the front of the leg and top of the foot being provided with long nibs, and the remaining needles being provided with short nibs, stitch forming cam mechanism for engaging the nibs of all the needles, means for supplying thread to the needles for circular and reciprocating work, vertically movable elevating and depressing cams for engaging the long nib needles, and means for shifting said cams at the beginning and conclusion of reciprocating work, of auxiliary raising and lowering cams located on opposite sides of the stitch forming cam mechanism, and movable into and out of operative relation with the long nib needles, a controlling cam operated in timed relation with the machine for bringing the auxiliary raising cam into operative position during certain predetermined courses of knitting, and means controlled by the pattern mechanism of the machine for moving both of said auxiliary cams into inoperative position, and holding them in inoperative position during reciprocating work, and during the knitting of the leg of the stocking.

9. In a stocking knitter, the combination with a circular series of needles, a group of needles for knitting the front of the leg and top of the foot being provided with long nibs, and the remaining needles being provided with short nibs, stitch forming cam mechanism for engaging the nibs of all the needles, means for supplying thread to the needles for circular and reciprocating work, vertically movable elevating and depressing cams for engaging the long nib needles, and means for shifting said cams at the beginning and conclusion of reciprocating work, of an auxiliary raising cam and an auxiliary lowering cam located on opposite sides of the stitch forming cam and movable into and out of operative relation with the long nib needles, an actuating lever for moving said cams into and out of operative relation, a controlling cam for operating said lever to move the auxiliary raising cam into and out of operative position during certain predetermined courses of knitting, and means controlled by the pattern mechanism for imparting additional movement to said lever, for moving the auxiliary lowering cam out of operative position, and holding both of said auxiliary cams out of operative position.

In testimony whereof I affix my signature. 120

WILLIAM E. SMITH.
